UNITED STATES PATENT OFFICE.

JOSEPH WARREN CUTLER, OF ROCHESTER, NEW YORK.

MAIL-CHUTE.

No. 820,394.

Specification of Letters Patent.

Patented May 15, 1906.

Application filed August 9, 1905. Serial No. 273,348.

To all whom it may concern:

Be it known that I, JOSEPH WARREN CUTLER, of Rochester, in the county of Monroe and State of New York, have invented certain new and useful Improvements in Mail-Chutes; and I do hereby declare the following to be a full, clear, and exact description of the same, reference being had to the accompanying drawings, forming a part of this specification, and to the reference-numerals marked thereon.

My present invention relates to windows or sight-apertures for receptacles or conduits, such as mail-chutes, through which articles are passed, embodying generally a tubular conduit extending vertically through a plurality of floors in a building and opening at its lower end into a mail box or receptacle, and has for its object to provide a transparent part or panel for permitting the inspection of the interior of such chutes and of such nature that not only may the manufacture of the device be facilitated, but the loss from breakage of the glass be reduced, and relatively small pieces of this expensive portion of the apparatus employed.

The invention has for its further object to apply the glass panels in such manner that not only is their application facilitated, but the production of ledges or interstices into which the corners of descending mail-matter might lodge is obviated.

In carrying out my invention in the preferred form the transparent glass panels are provided with inclined rounded or beveled edges and are applied in such manner that a portion of the panels near the edges projects inwardly beyond the inner wall of the chute or conduit in order that the descending mail-matter will not lodge or catch thereon.

To these and other ends the invention consists in certain improvements and combinations of parts, all as will be hereinafter more fully explained, the novel features being pointed out in the claims at the end of the specification.

In the accompanying drawings, Figure 1 is a front elevation of a portion of a mail-chute provided with my improvements. Fig. 2 is a vertical sectional view thereof. Fig. 3 is a horizontal sectional view. Figs. 4, 5, and 6 are front views of a modified form, and Fig. 7 is a horizontal view on the line $z-z$ of Fig. 6.

Similar reference-numerals in the several figures indicate similar parts.

While my invention is applicable to any of

the forms of mail-chutes in general use, I prefer to employ it, as shown, in connection with chutes of the general nature of those contained in Letters Patent No. 758,128, granted to me April 26, 1904, each chute-section being composed of a rear part or channel 1, formed of sheet metal and having at the forward portion narrow inwardly-projecting flanges 2, the front of the chute being preferably composed of a door, panel, or plate 3, either removable or stationary, preferably of sheet metal, and provided at the side edges with forwardly, outwardly, and inwardly extending flanges 4, adapted to fit over the flange 2 on the rear section in such manner that the joint between the abutting edges of the parts of the chute are protected, so that the corners or edges of mail-matter descending will not be liable to be caught.

11 indicates the usual mail-receiving aperture, located in the present instance in a chute-section having two panels of glass.

The front 3 of the chute is provided with preferably a plurality of apertures for the reception of the transparent panels or windows 5, said panels being each composed of a piece of plate or molded glass with its edges beveled or inclined inwardly or toward the center, either at a sharp angle or gradually rounded, and the size of said glass pieces is such relative to the openings in the said front that the inner faces will project inwardly beyond the inner wall of the chute or receptacle, as shown in Figs. 2 and 3, so that mail-matter will not lodge thereon, nor will the edges thereof catch in the joint between the panels and front of the chute or receptacle. These glass panels are also preferably inclined or rounded laterally of the chute at their upper portions, as shown, to afford the least-possible obstruction to descending letters. While these glass panels may be held in position by any suitable means, I prefer, if they are relatively large, to provide separate holding devices, such as frames 6, with their inner edges rounded over, as shown, projecting over the outer surface of the margin of the glass and bearing on the edges only, said frames being secured at their outer edges by any suitable means, such as screws or rivets 7, the inner heads of the latter being countersunk and substantially flush with the inner surface of the front plate in order that they may form no obstruction to the descending mail-matter. This feature of placing the smaller surface of the panel in a slightly larger aperture

is advantageous whatever may be the means for holding the panel, as the latter is self-seating, and the amount its inner surface projects is immaterial.

5 When the number of glass panels in the front of the chute is sufficiently large to warrant it, instead of forming a holding-frame for each panel I provide a securing metal plate or frame 8, having apertures corresponding to those in the front 3, with the bead or flange 9 extending over the edges of the outer surface of the glass, this more or less elastic portion formed by the bead serving to hold the glass panels firmly in place 15 without excessive pressure sufficient to break the edges and without the employment of packing material. This metallic plate may be secured to the front at intervals by rivets 10 or other suitable means, their inner heads 20 being countersunk, as before described, to prevent obstructions in the chute.

It is immaterial, so far as my invention is concerned, what the shape or number of the glass panels is, as they may be polygonal or 25 rounded, as shown in Figs. 5, 6, and 7; but, as stated, it is preferable that the upper portion, with which the descending mail-matter is liable to come in contact, should be curved or inclined, as shown.

30 I claim as my invention—

1. The combination with a mail-receptacle forming a passage for postal matter, and provided with an aperture therein, of a panel fitted within said aperture having its upper 35 edge inclined and its inner surface below said edge projecting inwardly beyond the inner wall of the receptacle.

2. The combination with a mail-chute provided with an aperture therein, of a panel 40 fitted within said aperture having its upper edge inclined inwardly toward the interior of the chute, and its inner surface below said edge extending inwardly beyond the inner wall of the chute.

45 3. The combination with a mail-receptacle provided with an aperture in one of its walls, of a panel fitted within said aperture having its upper edge adjacent said aperture extending inwardly beyond the inner surface of said 50 wall and inclined downwardly toward the interior of the receptacle and also inclined downwardly toward the side of the receptacle.

4. The combination with a mail-receptacle provided with an aperture in one of its walls,

of a panel fitted within said aperture having 55 its edges inclined toward the center of the inner face of the panel and with its inner surface smaller and its outer surface larger than the aperture, and a holding device engaging the outer face of the panel to secure it in position.

5. The combination with a mail-receptacle having a plurality of apertures in one wall thereof, of a corresponding plurality of transparent panels for said apertures having their 60 edges inclined, and their inner faces being the smaller and arranged inwardly beyond the wall of the receptacle and a securing-frame 65 engaging the outer faces of the panels near their edges.

6. The combination with a mail-chute having an aperture in the wall thereof, of a transparent panel for said aperture having the beveled edges and arranged with its smaller 70 surface within the chute, and a securing device 75 engaging the outer surface of the panel.

7. The combination with a mail-chute having an aperture in the wall thereof, of a transparent panel for said aperture having the beveled edges and arranged with its smaller 80 surface within the chute and a frame secured to the chute and having the curved flanges at the inner side for engaging the outer surface of the panel.

8. The combination with a mail-chute having a plurality of apertures in the wall thereof, of a plurality of transparent panels for said aperture provided with beveled edges and having their smaller inner surfaces near their 85 edges arranged within the chute, and a securing-frame for the panels having apertures 90 and the flanges at the edges thereof extending over and engaging the outer surfaces of the panels.

9. The combination with a mail-chute having a plurality of apertures in the wall thereof, of a plurality of transparent panels for said apertures provided with beveled edges and having their smaller inner surfaces near 95 said edges arranged within the chute and a securing-frame for the panels having apertures 100 and the curved flanges at the edges thereof extending over and engaging the outer surfaces of the panels.

JOSEPH WARREN CUTLER.
